MATCH BOOK HOLDER

Filed March 8, 1927

Attorney

UNITED STATES PATENT OFFICE

JOSEPH KLECAK, OF ISLIP, NEW YORK

MATCH-BOOK HOLDER

Application filed March 8, 1927. Serial No. 173,654.

This invention relates to match book holders.

It has become the custom of certain business persons and business corporations to distribute matches in the shape of match books wherein the match books are made of heavy paper or fiber and are securely attached together and to the book cover. These matches are broken off from the book and when the book is empty, the cover is thrown away. These match books are provided at the bound edge with a scratching surface extending across the book and the parts of the book are usually secured together with a binding staple.

These match books are, for the most part, made in the same way and are of substantially the same width. They vary slightly in thickness.

Various means have been provided for enclosing these match books but these are, by some persons, regarded as inconvenient because the box has to be opened before the book may be opened. In addition, these boxes are considered by some to be too costly and to have too much bulk.

The primary object of my invention is to produce an improved match book holder which will be very simple, easy to operate, and inexpensive.

Another object of my invention is the provision of an improved match book holder having means for holding the book firmly in place after insertion.

Another and still further object of my invention is the provision of an improved match book holder having means for engaging the binding of the match book as the latter is inserted, and in such a way that it is automatically held after mere insertion.

Another and still further object of my invention is the provision of an improved match book holder having means for engaging bindings of match books of various man-

ufacture which may be by accident or because of the design of the book making machine, have the bindings at various places on the book. Other and further objects of my invention will be apparent to those skilled in the art from a reading of the com-

plete specification and claims. Referring to the drawing wherein I have illustrated embodiments of my invention.

Fig. 1 is a front view of my invention having a match book held therein, the match book cover being open.

Fig. 2 is a front view of the articles shown in Fig. 1 but having the match book cover closed.

Fig. 3 is a rear view of the article shown in Figs. 1 and 2.

Fig. 4 is a side view of the same.

Fig. 5 is an enlarged view of a preferred form of my invention.

Fig. 6 is an enlarged cross section on the line 6—6 of Fig. 5 but showing a fragmentary view of the match book in place.

Fig. 7 is a view similar to Fig. 6 but without the book.

Fig. 8 is a front view of a slightly different form of my invention.

Fig. 9 is a view of a modification showing a larger back member than is shown in the other forms.

Throughout the views of the drawing, the same or similar parts are designated by the same reference characters.

Referring to Figs. 1 to 7 inclusive, 10 designates a securing means by which my holder may be attached to any suitable securing means as the end of a watch chain opposite to the watch end. In my preferred form, I have illustrated a holder having a front portion of a rim extending along the sides and top, to permit the scratching surface of the match book to be exposed for use. This is clearly shown in Figs. 1 and 2 wherein the sides of the front are designated 11 and 12 respectively and the edge of the top as 13.

The top 14 extends from the edge 13 and, in the form shown, is a continuation of the back 15. The back of the holder may be joined to the sides of the front as illustration at Fig. 4.

The usual construction of match books comprises a pack of matches cut, from fiber, into strips 16 the width of a match, the ends being dipped to form the match heads 17. These packs are then fastened together by a suitable binding as by the cover 18 and the

staple 19. In assembling, it is customary for two or more layers of the matches to be placed in the cover, one end of which is folded over as at 20, after which the staple 19 is set. This latter operation completes the binding of the match book. Across the exposed portion of the fold 20 is a suitable scratching face 21, upon which to strike the matches.

10 The length of the side portions 11, 12 is such as to reach about to the bottom of the scratching surface 21. It is to be noted that the lower ends 11^a, 12^a, flare outwardly as clearly shown in Fig. 6. This feature is to permit the insertion of the cover portion 18^a outside of the scratching surface 21 of the fold 20 when the match book is in place in the holder.

15 In order to properly hold the match book in the holder, I have provided a holding means which preferably permits ready insertion of the match book but prevents its ready removal. An example of this holding means is illustrated in Figs. 2, 5, 6 and 7. 20 The back member 15 is provided with a slot forming the tongues 22, 23, 24 which tongues are pressed into the space within the holder. These tongues are preferably so positioned that their points are of different distances 25 from the top 14 and also of different distances from the back from which they are pressed.

30 It is to be noted that the tongues point toward the top of the holder. This construction permits the ready insertion of the match book, the tongues being merely pressed backwardly a slight distance and the book being bent forwardly slightly to permit easy movement of the book within the holder. The 35 securing element as the staple 19, when it passes one or more of the tongues 22, 23, 24, will be trapped and the ready removal is prevented. If the securing element as the 40 staple 19 is near the edge of the book, then it will go past the upper tongue 23 and be held thereby. If it does not go that far, it 45 may be caught by one or both of the tongues 22, 24. In addition, if the tongues 22, 23, 24 not in engagement with the securing element, are properly shaped, they may engage 50 the cover itself and offer a holding action against ready removal.

55 When it is desired to remove a match book from the holder as when the matches are all used therefrom, it is possible to do so by pressing the back of the book below the tongues. Then if the holder is constructed with no solid metal portion connecting the lower portions of the sides 11, 12 of the front, 60 this removal operation is not difficult. However this intentional removal does not prevent the tongues from effectually preventing accidental removal.

65 In Fig. 8, I have illustrated a slight modification. The parts 110, 111, 112, 113, 114,

115 correspond to the parts 10, 11, 12, 13, 14, 15 of Figs. 1 to 7. The tongues 122, 123, 124 are similar to the tongues 22, 23, 24 of Figs. 3 and 5 with the distinction that their respective upper extremities are all of different distances from the top 114 of the holder. This construction assures the engagement of the securing elements as the staples 19, through a greater range, or if the tongues are close together as to height, they cause greater 70 chance of securing the book with its top adjacent the 14 of the holder.

75 In the modification shown in Fig. 9, the parts 210, 211, 212, 213, 214, 222, 223, 224, correspond respectively to the parts 10, 11, 12, 13, 14, 22, 23 and 24 already described. The back 80 215 however is different and extends lower than the backs 15 and 115 previously described.

85 In use, it is only necessary to force the bound end of a match book into the holder. The tongues 22, 23, 24, 122, 123, 124, 222, 223, 224, as the case may be, will permit the free entry of the book. However any tendency to remove the book is immediately resisted by the tongues and particularly by the last tongue over which the securing element as the staple 19 passes. This last tongue would 90 securely hold the book in place by engagement with the securing element. The construction wherein the tongues extend into the space within the holder at varying distances, is believed to operate advantageously as if placed so as to extend the same distance into the housing, in practice, the upper one has 95 found to interfere with the proper functions of the lower ones.

100 While I have described and illustrated embodiments of my invention, I desire to have it understood that I do not limit myself to the exact showing and that modifications and changes may be made without departing from the spirit of my invention and within the scope of the appended claims.

105 Having described my invention, what I claim and desire to secure by Letters Patent of the United States, is:—

110 1. A match book holder of a size and shape to receive a match book, tongues at different distances from the top of the holder to accommodate for the different spacing of the binding means in match books and having their ends in the path of the match book and in position to yield easily to permit the 115 insertion of the match book and having respective edges in position to grip the book when any tendency exists to withdraw the same from the holder.

120 2. A match book holder having a back and of a size and shape to receive a match book, a plurality of yieldable-tongues struck up from the back of the holder and having their outer ends in the path of the match book and extending upwardly and inwardly toward the book space of the holder to yield to per- 125 130

mit of the easy insertion of a match book and having edges of a height so that the binding staple of the book where the latter is inserted will pass beyond one or more of the 5 tongues and will engage the staple if force is used tending to withdraw the book.

In testimony whereof I hereunto affix my signature.

JOSEPH KLECAK.
